UNITED STATES PATENT OFFICE.

JOHN GEORGE SMITH, OF MONTREAL, QUEBEC, CANADA, ASSIGNOR TO
GARTH & CO., OF SAME PLACE.

HEATING APPARATUS.

SPECIFICATION forming part of Letters Patent No. 357,793, dated February 15, 1887.

Application filed April 19, 1886. Serial No. 199,301. (No model.)

To all whom it may concern:

Be it known that I, JOHN GEORGE SMITH, of the city of Montreal, in the District of Montreal and Province of Quebec, Canada, mechanical 5 engineer, have invented certain new and useful Improvements in Heating Apparatus; and I do hereby declare that the following is a full, clear, and exact description of the same.

My invention has reference to the special 10 means used to heat public or private buildings, and is equally applicable to steam or hot-water systems.

In place of the box-coils, pipe-circulations, or chambers connected together by hollow 15 standards, I propose to substitute a cluster of vertical sections so constructed and secured together that each section shall have a separate and positive circulation of its own, the whole combined forming a radiator, the inlet 20 and outlet being at the same end of said radiator.

My invention consists in a radiator formed of independent sections, each having proper 25 vertical passages for steam, with inlet and outlet passages which communicate with all the sections. In connection with these it also includes an air-pipe, which extends through the sections and communicates with each, and is provided with an air-valve which permits 30 the escape of air from all the sections, and certain details of construction which are fully hereinafter described.

For full comprehension of my invention reference must be had to the annexed drawings, 35 in which—

Figures 1 and 2 show vertical transverse sections through one section of the radiator, and Fig. 3 a side view partially broken away.

Similar letters of reference indicate like 40 parts.

A is a section, composed in this case of legs A', A², and A³, the first of these being nearest to the inlet and the last to the outlet.

a a and a' a' are the faced joints.

45 B B' are apertures formed in the base corresponding exactly in size and position to each section.

Through the openings B B passes the inlet-pipe C, connected with any desired source of 50 supply, whether of steam or hot water, and

communicating with the inlet-leg A' of each section through small apertures c on its top side. The outlet-pipe D, communicating with the several sections through the apertures d on its side, is taken through the openings B' 55 B' and out of the same end of the radiator as the inlet.

B² B² are openings near the top of each section, through which passes the pipe E, for taking off the air, e e being openings into it, and 60 E' the air-cock at end of the pipe.

G is a diaphragm extending downward from the top side of chamber near leg A', and reaching, as in Fig. 2, into a recess or pocket, H, constructed in the bottom of the chamber, thus 65 forming a trap or water seal. The same object—viz., a water seal—may be attained, as shown in Fig. 1, by the substitution for the extra length of the diaphragm G and the recess H of a secondary diaphragm, G', projecting 70 upward from the bottom plate. By the construction of these diaphragms, and with or without the pipes C D, the flow and return are practically separated, so that the sectional radiator above described and shown can be 75 used for steam as well as hot water, and this particular feature may be utilized in radiators of differing construction.

I prefer to place between the faced joints A A and A' A' of the sections rubber or other 80 washers, H' H', fitting tightly on the pipes C, D, and E.

The operation of the invention will be easily understood from the foregoing and the accompanying drawings. The hot water or steam 85 passes through the holes c in the inlet-pipe C into the leg A' of each section, and thence, as shown by the arrows, till through the holes d it enters the outlet-pipe D and passes off. By this means a positive separate and individual circulation is set up in each section, and this will be the case even if the pipes C and D are omitted and the inflow of steam or hot water be through the openings B corresponding closely to each other, and the outlet 95 through the holes B', the faced joints a a and a' a' being fitted closely together.

Having thus described my invention, I beg to state that what I claim is as follows:

1. A radiator formed of independent sec- 100

tions, each having vertical steam-passages, with inlet and outlet passages at the bottom and on opposite sides extending through all the sections and communicating with each, an air-pipe extending through the upper portion of the radiator-sections and communicating with each, and an air-valve to permit the escape of air from all the sections, substantially as described.

10 2. A radiator formed of independent sec-

tions, each having circulating passages, inlet and outlet pipes C D at the bottom, and a vent-pipe, E, at the top, all passing through and communicating with the sections and securing them together, substantially as described.

JOHN GEORGE SMITH.
